UNITED STATES PATENT OFFICE.

ELZA HOWARD COPEN, OF AKRON, OHIO.

SHAKER.

1,391,096.

Specification of Letters Patent. Patented Sept. 20, 1921.

Application filed September 3, 1920. Serial No. 407,874.

To all whom it may concern:

Be it known that I, ELZA HOWARD COPEN, a citizen of the United States, residing at 296 Euclid avenue, in the city of Akron, in 5 the county of Summit and State of Ohio, have invented certain new and useful Improvements in Shakers, of which the following is a specification.

My invention relates to improvements in 10 shakers and the object of the invention is to devise a shaker in which the container is so divided as to permit the alternate use of two different seasonings such as salt and pepper. A further object is to provide means in the 15 bottom of the container for filling each of the compartments therein.

My invention consists of the parts constructed and arranged substantially as hereinafter more particularly described and 20 illustrated in the accompanying drawing in which:

Figure 1 represents a plan view of the shaker constructed according to my invention.

Fig. 2 is a side elevation thereof.

Fig. 3 is a vertical section therethrough showing the dividing partition.

Fig. 4 is an enlarged sectional view showing the means for mounting the swingable 30 cover.

Fig. 5 is a detail of one of the screws forming the trunnions of the cover, the said screw being split longitudinally for a portion of its length.

Fig. 6 is an inverted plan view of the shaker showing the closures for the filling holes of the respective compartments thereof, the left hand closure being shown in the closed position and the right hand closure 40 in the open position.

Fig. 7 is a sectional detail of the bottom of the shaker showing the closure applied to one of the filling holes.

Like characters of reference indicate corresponding parts in the different views.

1 is the container of the shaker having a dome shaped top 2 with perforations 3 extending therethrough. 4 is a vertical partition dividing the container 1 of the shaker 50 into two separate compartments designed to

contain different seasonings. 5 are filling holes in the bottom of the container through which the respective compartments are filled. 6 are suitably hinged closures having raised surfaces 7 conforming in shape 55 with the filling holes and adapted to enter such holes when the closures are applied thereto.

8 is a cover provided with the lugs 9, said cover covering substantially half the dome shaped top 2 of the container and conforming in shape therewith, said cover being pivotally mounted on the top 2 by the screws 10, which are screwed into the top and extend through orifices 11 in the cover. The 60 screw 10 is split longitudinally for a certain extent in order that when the screws are inserted into the orifices 11 they will engage the walls of such orifices and thus prevent the cover 8 from being swung over too 65 easily.

My device is used as follows:

When it is desired to use the seasoning out of one compartment the cover 8 is swung over so as to cover the perforations 3 at 70 the top of the other compartment, thus closing them and preventing any seasoning from that compartment getting out while shaking the shaker in the usual manner.

When it is desired to use the seasoning 80 in the other compartment it is merely necessary to swing the cover over by means of the lugs 9 when seasoning will be shaken out.

From the above description it will be seen 85 that I have devised a simple and effective shaker which can be used for containing two distinct seasonings such as salt and pepper.

It is to be understood that my shaker can 90 with equal facility be used for other purposes than for seasoning such as for flour, spices and such like.

What I claim as my invention is.

A container having an integral perforated 95 dome-shaped top and a partition wall extending between said top and the bottom wall of the container and dividing the latter into separate compartments, each compartment being provided with an individual fill- 100

ing opening, a closure plate conforming in shape to said top and movable thereover to permit discharge from one compartment while preventing discharge from the remaining compartment, pivot screws passing through said closure plate and threadedly engaged in the dome-shaped top, said screws

being split longitudinally to frictionally engage the openings provided therefor in the closure plate whereby the latter is held from moving too freely relative to the container.

In testimony whereof I affix my signature.

ELZA HOWARD COPEN.
